UNITED STATES PATENT OFFICE.

JOHN W. CONNOLLY, OF NEW BEDFORD, MASSACHUSETTS.

PROCESS OF REMOVING IMPURITIES FROM FIBROUS MATERIAL.

1,119,069.

Specification of Letters Patent.

Patented Dec. 1, 1914.

Application filed November 20, 1911. Serial No. 661,196.

To all whom it may concern:

Be it known that I, JOHN W. CONNOLLY, a citizen of the United States, residing at New Bedford, in the county of Bristol and 5 State of Massachusetts, have invented certain new and useful Improvements in Processes for Removing Impurities from Fibrous Material, of which the following is a specification.

10 This invention relates to a process for removing impurities such as sand, leaves, seeds, dirt, naps or knits, burs, short or undesirable fibers, and foreign matter of any kind from cotton, wool, worsted, silk, flax, 15 linen, jute, hemp, and other fibrous materials, said process also including the laying of the fibers parallel with each other, and the glossing or polishing of certain fibrous materials which are susceptible of a gloss or 20 polish.

In carrying out the process a sheet of fibers is held by, or between, two feed rolls, one or both being either smooth or fluted, and made of metal or any other suitable material; or 25 one or both of the rolls being wound or covered with leather or some other desirable material; or said sheet of fibers may be held between one roll, as herein described, and a round or flat rod, or surface or edge of a 30 knife, plate, bar, or board. The sheet of fibers may also be held between nippers or jaws which open to allow the sheet to be fed or propelled through said nippers or jaws for the distance desired, after which the nippers or jaws may close to again hold the 35 sheet.

A current of air or steam is drawn or forced through a slot, into a stationary or 40 revolving hollow roll, tube, pipe, cylindrical or other shaped casing. The slot is held in close proximity to the fibers, and to the bite of the nippers, whereby the impurities, etc., are drawn or forced from the sheet into the slot, and carried away to be cared for by 45 suitable receiving machinery. The ends of the fibers which lead or project from the nippers first will hereinafter, for convenience, be termed the heads of the fibers; whereas the opposite ends, or those which leave the 50 nippers last, will be termed the tails of the fibers.

After the heads of the fibers have been treated as herein described, the nippers holding the sheet of fibers, are brought closer to, or become closer to, a set of receiving rolls. 55 This set of receiving rolls rotates at a suf-

ficient rate of speed to take a firm hold on the heads of the fibers, so that now the sheet of fibers is held by both the feeding and receiving sets of rolls. If it is not desired to break the fibers, thereby reducing the length of the individual fibers, the distance from the bite of the feed rolls to the receiving rolls should be greater than the length of the fibers being treated. In this case the sheet 60 of fibers is held together by the cohesion of the individual fibers, and the fibers are not broken by the next operation. In the next operation the feed rolls and nippers are moved away from the receiving rolls; 65 or both sets of rolls are revolved in a reverse direction to, but in a lesser degree than the forward motion, so as to disconnect, or partially disconnect those fibers which are held by the receiving rolls, from the fibers which 70 are being held by the feed rolls. The tails of those fibers whose heads have been already treated, and which are now held by the receiving rolls, may now be treated by a current of air or steam being drawn or 75 forced through the same, or another slot, in the same hollow roll or pipe already described, by which the heads of the fibers were treated; or by a current of air or steam being drawn or forced through a slot in another or 80 second hollow roll or pipe which may be similar to the one already described. The tails of the fibers are treated by the slot being held in close proximity thereto, and to the bite of the receiving rolls. While the 85 tails of the fibers are being treated, or a period of time before or after such treatment, the heads of the fibers of the remaining portion of the sheet, which are now held by the feed rolls, may be treated, thus completing the cycle of operation, or technically, 90 one nip. The operation is continuous, every subsequent cycle or nip being the same as the first, except that after the heads and tails of the first section have been treated, the 95 heads of the next section are caused, or may be caused, as desired, (governed by the order and relative time of the various motions) to overlap the tails of the preceding section a greater or less distance, thus making a continuous sheet of fibers delivered from the 100 machine.

Having now outlined in a general way the process, I will proceed to describe the same more in detail, reference being had to the 110 accompanying drawings, in which—

Figures 1 to 9 are diagrammatic views

illustrating the several steps of the process, and the mechanism for carrying out the same. It is to be understood, however, that I do not desire to be limited to the particular apparatus shown.

In the drawings, A denotes the upper jaw of the nippers; B, the lower jaw; C, a feed roll; D, a feed plate; E, a screw for adjusting the feed plate; F, an air tube with slot f; and H, the receiving rolls. A side elevation of these parts is shown, and it will be understood that they may be of any desired length according to the width of the sheets of fibers to be treated. The machine 10 itself may be run as a unit; or a number of units may be connected to run together.

Fig. 1 shows the position of the parts at the commencement of the operation, and Fig. 2 shows their relative position when 20 the heads of the fibers are being treated. The feed roll C has fed the sheet forward or rotated sufficiently so that the fibers are projecting beyond the closed jaws A and B of the nippers, a certain distance, say, for 25 instance, three-eighths of an inch. The slot f for the entrance of air or steam is directly under the bite of the nipper jaws. By a suitable valve mechanism (not shown) air or steam is allowed to pass through the 30 slot f into the tube F at the desired velocity. In so doing the air will draw or force the projecting ends or heads of the fibers into the slot f, but cannot carry them away, as they are held firmly by and between the nipper 35 jaws. However, impurities or foreign matter, contained in and among the projecting portion of the fibers will be carried away into the tube F. The valves are now automatically closed so as to stop, for a time, the 40 passage of air or steam into the slot, and the nipper jaws will open, and together with the feed roll C and feed plate D will be moved closer to the receiving rolls H, as shown in Fig. 3.

Fig. 3 shows the position of the parts when the heads of the fibers which have been treated are being taken hold of by the receiving rolls H. The jaws of the nippers have opened and been brought very close to 50 the bite of the receiving rolls, thus extending the sheet of fibers toward and into the bite of the receiving rolls, which latter rotate a certain surface distance of say, five-sixteenths of an inch. At or about the same 55 time, the feed roll C rotates a certain surface distance of, say, three-eighths of an inch, and there is now a connected sheet of fibers from feed roll C and plate D to rolls H. The distance between these two 60 points, however, is always greater than the length of the longest fibers in the sheet, so that only the connection of the fibers, and not the individual fibers are broken in the next operation, which is, that the nippers, 65 together with the feed roll and plate, will

be backed away from the rolls H as shown in Fig. 4, whereupon the sheet of fibers is separated between the feed rolls and the receiving rolls. The nippers and the feed roll and plate have been moved away from the receiving rolls H, thereby detaching the fibers in such a manner that the tails of the fibers of one section are held between the receiving rolls, and the heads of the fibers of the other section are protruding from the nipper jaws A and B, which latter are still open. The nipper jaws are now made to close, thereby holding the untreated portion of the fibers secured, the severed section being held by the rolls H. The air tube 70 F is now moved toward and in close proximity to the bite of the rolls H, as shown in Fig. 5, and the tails of the fibers protruding from said rolls are treated, the valves opening to cause or allow air or steam to pass 75 through the slot f so as to draw or force the tails of the fibers into the slot and thereby remove the impurities, without, however, carrying the fibers away, as they are held by the rolls H. The valves are now made 80 to close, and the tube F is moved away from the rolls until it is in its first position under the closed nipper jaws as shown in Fig. 6. The valves are now again opened to admit air to the slot f and the heads of the 85 fibers held by the nippers are cleaned as before, after which the valve closes; and the nipper jaws are made to open, and said jaws together with the feed roll C and plate D are moved closer to the rolls H, as shown in 90 Fig. 7.

Fig. 7 shows the position of the parts when the heads of the fibers which have just been treated are taken hold of by the rolls H, said parts taking the same position as in 105 Fig. 3, except that there were then no fibers held by the rolls H, whereas now, and in each subsequent position similar to Fig. 7, there are fibers held by the rolls H, so that the heads of the fibers which protrude from the open nipper jaws lie over or under, or intertwine with the tails of the fibers which are held by the rolls H. At this time the rolls H again rotate, and at or about the same time, the feed roll C rotates as previously explained, so that the fibers are delivered from the rolls H in a connected sheet. The nippers, together with the feed 110 roll and plate are now made to recede from the rolls H, as shown in Fig. 8.

Fig. 8 shows the position of the parts when another section of fibers has been disconnected or severed from the sheet, this position being the same as shown in Fig. 4, which completes the cycle of operations, 115 every subsequent cycle or nip being similar to the one herein described. The various moving parts will be automatically driven and controlled by suitable mechanical means. If a fine comb is used, it will be lo- 120 130

cated between the feed and the receiving rolls so as to straighten out the fibers that are being drawn into the latter, and to retard the progress or passage of the impurities and foreign matter, thereby increasing the efficiency of the air slot *f*. If air or steam is to be forced into the slot *f*, the nippers, feed and receiving rolls, and the air or steam tube, will be inclosed in an air or steam tight compartment in which the air or steam will be kept at the desired pressure, provision being made for the ingress and egress of the fibrous material.

In the foregoing description it is stated that the heads and tails of the fibers are subjected to the cleansing blast, but it will be noted that the intermediate portions of the fibers are also treated. When the tails are held by the nippers, not only are the heads treated but also the intermediate portions, in fact all parts of the fibers, except the almost extreme tail ends, which are held fast. When the heads are held by the receiving rolls, both the tails and intermediate portions are treated. In other words, two-thirds (more or less) of the length of the fibers from one end is protruding at the first operation, and the same length of fiber from the other end at the next operation.

Fig. 9 shows combs I on opposite sides of the slot *f* in the tube F. The points of the teeth of the comb extend in the direction of the cleansing blast, but at an angle thereto.

The herein-described process also results incidentally in imparting a polish to the fibers, this being effected by the friction of the fibers upon being drawn apart, and by the friction of the steam or air current upon the fibers.

I claim:

1. The process of removing impurities and the like from fibrous material, which consists in successively dividing a sheet of such material into sections, and subjecting each succeeding section to the action of a cleansing blast, and then re-uniting each section with the previous one subjected to the cleansing blast to re-establish the continuity of the sheet.

2. The process of removing impurities and the like from fibrous material, which consists in dividing a sheet of such material into sections, and after each division subjecting first one and then the other end of the successive sections thus severed from the

sheet to the action of a cleansing blast, and after such cleansing operation uniting the sections to the sheet, to re-establish the continuity thereof.

60

3. The process of removing impurities and the like from fibrous material, which consists in subjecting the forward end of a sheet of such material to the action of a cleansing blast, then severing a section from the sheet and subjecting the rear end of such severed section to the action of the cleansing blast, then subjecting the severed end of the remaining portion of the sheet to the cleansing blast, and then uniting the last mentioned end of the sheet to the section which was severed.

70

4. The process of removing impurities and the like from fibrous material, which consists in subjecting the forward end of a sheet of such material to the action of a cleansing blast, then severing a section from the sheet and subjecting the rear end of such severed section to the action of the cleansing blast, then subjecting the severed end of the remaining portion of the sheet to the cleansing blast, and then uniting the last mentioned end of the sheet to the section which was severed, then advancing the sheet and again severing a section therefrom and repeating the herein-described operation, the same being continued to the end of the sheet.

75

5. The process of removing impurities and the like from fibrous material, which consists in dividing a sheet of such material into sections, and subjecting the sections to the action of a cleansing blast and also to a combing action, and then reuniting the sections to re-establish the continuity of the sheet.

80

6. The process of removing impurities and the like from fibrous material, which consists in dividing a sheet of such material into sections, carrying a cleansing blast first to one and then to the other end of the severed sections to subject said ends to the action of the blast, and reuniting the sections after such cleansing action to re-establish the continuity of the sheet.

85

In testimony whereof I affix my signature in presence of two witnesses.

JOHN W. CONNOLLY.
